John J. Hanrahan
ATTORNEY

UNITED STATES PATENT OFFICE

HENRY C. COX, OF KEW GARDENS, NEW YORK, ASSIGNOR TO COLUMBIA PHONOGRAPH COMPANY, INC., OF BRIDGEPORT, CONNECTICUT, A CORPORATION OF NEW YORK

ENVELOPE

Application filed September 25, 1928. Serial No. 308,155.

This invention relates to new and useful improvements in containers or envelopes for disc phonograph records.

An object of the invention is to provide a package or "carry home" envelope which will also serve as a filing or storage envelope.

An additional object is to provide a "carry home" or package envelope which may be readily converted into an envelope for use in housing or storing the record when the latter is filed or otherwise not in use.

A more specific object is to provide a "carry home" envelope which is constructed and perforated or marked or weakened in a particular manner and along definite lines, in order that it may be easily torn or cut along its perforated, marked or weakened lines, and converted into a storage envelope of usual appearance.

With the foregoing and other objects in view, as will become more apparent as the description proceeds, the invention consists in certain features of construction, combination and arrangement of parts as will be hereinafter more fully described and claimed.

Referring to the accompanying drawing forming part of this application:—

Fig. 1 is a face view of an envelope constructed in accordance with the present invention;

Fig. 2 is a vertical sectional view on the line 2—2 of Fig. 1;

Fig. 3 is a face view of the upper portion of a different envelope having the invention applied thereto; and

Fig. 4 is a sectional view on the line 4—4 of Fig. 3.

Referring in detail to the drawing, and particularly to Figs. 1 and 2 thereof, the envelope is shown as comprising a body portion 5 and an upper or closure portion 6 including a flap 7 formed integral with the back 8 of the envelope. This flap is adapted to be turned over the upper edge of the front wall 8^a of the envelope, as clearly shown. The side edges of the envelope are of course sealed and the bottom is sealed as by the flap 9. Since the walls 8 and 8^a are not secured at their upper edges, this being the entrance

to the envelope, flap 7 is used to close the envelope during transportation.

This flap may be sealed closed or, as shown in the drawing, the flap may carry a button 10 having a string 11 secured thereto and adapted to be wound around a similar button 12 secured to the front wall 8^a of the envelope.

The envelope, as just described, is designed for the purpose of carrying articles and in the present instance, a disc phonograph record indicated at 13. Both the front and rear walls 8^a and 8 respectively of the envelope, are perforated along the line 14 which it will be noted, is below the button 12. Line 14 preferably, although not necessarily, dips downwardly at the center of the envelope as suggested at 15, for a purpose which will be described.

After the record 13 has been carried home in the envelope, it is but necessary to tear the envelope along the perforated line 14 in order to sever the upper portion from the lower portion thereof. On this being done, the lower or body portion 5 has the appearance of the usual record envelope and is cut away as shown by the dip 15 whereby the upper edge of the record will project slightly to facilitate the removal of the record from the envelope.

To enable the user to read the usual label on the record at the center thereof, I have perforated the walls 8^a and 8 along the line 16. When this central portion of the envelope is removed, the record label is exposed and the title of the record, name of the composer and so forth may be read without removing the record from the envelope.

Figs. 3 and 4 show the upper portion of an anchor common "carrier home" type of envelope includes two handle portions 17 and 18, one of which, 18, passes through a slot in a closing flap 19 of the envelope.

The envelope shown in Figs. 3 and 4 is perforated along the line 14, and provided with a dip 15 as in the figures first described, and for a like purpose.

The body portion 5 of my improved envelope is of such width as to snugly receive a record in the manner in which the record is

now received in the usual filing or storage envelope. Further, the perforated line 14 is spaced from the bottom or opposite edge of the envelope a distance approximately equal to the diameter of a record or to the width of the envelope. It will be understood that the dimensions of the envelope have been described with reference to the diameter of a record since records are made in various diameters.

10 While I have chosen to illustrate the invention by showing a perforated line at 14, it is to be understood that this line may simply be indicated or the envelope may be weakened 15 at this point other than by perforating it or any other arrangement for accomplishing the purpose may be utilized. When the line is simply indicated the envelope is preferably cut as by a pair of scissors, a knife or the like.

20 From the foregoing description taken in connection with the accompanying drawing, it will be noted that I have provided an envelope which serves two purposes. When a record is purchased, the dealer merely inserts 25 the record into a "carry home" envelope, and when the customer reaches home, it is but necessary for him to tear the envelope along the line 14 and to remove the center disc portions by tearing along the line 16, in order that he 30 may have a storage envelope of the usual design.

It is pointed out that the present practice provides for the shipping to the dealer of a disc phonograph record in an envelope the 35 same in construction and appearance as the body or bottom portion 5 of the envelope illustrated. When the dealer sells the record, he must package it, and it is common practice for him to insert the record and envelope into 40 a larger "carry home" envelope. This means that two envelopes go with each record, one of which, the "carry home" envelope, is destroyed by the purchaser, and the other of which forms a permanent storage or housing envelope 45 for the record.

According to the present invention, but one envelope goes with the record, and when the purchaser reaches home, by a simple operation he converts it from a "carry home" to a storage envelope, the storage envelope saving the record from scratch and preventing its music lines from becoming filled with dust and otherwise protecting the record.

50 While the invention has been described in detail in its application to the type of envelope illustrated, this particular type of envelope has been selected merely for the purpose of disclosing the application of the invention. It is therefore to be understood that the invention 55 may be applied to types of envelope other than those disclosed, without departing from the spirit of the invention or the scope of the appended claims.

Having thus described my invention, what 60 I claim is:—

1. An envelope for disc phonograph records, the same being of a width approximately equal to the diameter of a record and being of a height greater than the diameter of a record, said envelope being open at one side, a flap for closing said side, and said envelope being perforated along a line to permit separation of the flap portion from the body portion and along a line to expose a portion of the record. 70

2. An envelope for disc phonograph records, said envelope comprising a body portion of a size to snugly receive a disc record and permit a portion of one edge thereof to extend beyond the body portion, said envelope including a closure portion secured to said body portion along said edge, and said envelope being perforated along a line corresponding with said edge to permit the ready separation of said closure portion from said body portion. 80

3. An envelope for disc phonograph records, the envelope comprising a body portion open along one edge, said body portion being of a width and height substantially equal to the diameter of a record to be placed in said envelope, said envelope including a closure portion along the open edge of said body portion, and said envelope being perforated along the said open edge of the body portion. 90

4. An envelope as in claim 3, the body portion having a line of perforations to facilitate the removal of a portion of the envelope to expose the label of a record when placed in the body portion. 95

5. An envelope for disc phonograph records the same comprising a body portion and a closure portion, said body portion being of a height approximately equal to the diameter of a phonograph record, and said envelope being marked along a line denoting the limit 100 of the body portion and the beginning of the closure portion, whereby when said envelope is severed along said line the closure portion is removed and storage to fit the record is provided. 110

6. An envelope for disc phonograph records, said envelope adapted to be used as a package envelope and as a filing envelope and comprising a body portion of a width approximately the same as the diameter of a record, said body portion being of a height approximately equal to said width, and a closure for said body portion for use when the envelope is used as a package envelope, said closure adapted to be removed to convert said envelope into a storage envelope. 115

Signed at New York, in the county of New York and State of New York, this 18th day of September, A. D. 1928.
